UNITED STATES PATENT OFFICE

166,369

SMOKER'S ACCESSORY

Elmer L. White, Evanston, Ill.

Application November 12, 1949, Serial No. 5,994

Term of patent 14 years

(Cl. D85—4)

To all whom it may concern:

Be it known that I, Elmer L. White, a citizen of the United States, residing in Evanston, in the county of Cook and State of Illinois, have invented a new, original, and ornamental Design for a Smoker's Accessory, of which the following is a specification, reference being had to the accompanying drawing, forming part thereof.

Fig. 1 is a perspective view of a smoker's accessory, showing my new design;

Fig. 2 is a top plan view;

Fig. 3 is a front elevational view;
Figs. 4 and 5 are opposite side elevational views;
and

Fig. 6 is a rear elevational view thereof.
I claim:

The ornamental design for a smoker's accessory, substantially as shown.

ELMER L. WHITE.
